(57) **CLAIM**

The ornamental design for a dental tool reader, as shown and described.

DESCRIPTION

FIG. 1 is a perspective view of a dental tool reader of the present invention;

FIG. 2 is a top view of the dental tool reader shown in FIG. 1;

FIG. 3 is a bottom view of the dental tool reader shown in FIG. 1;

FIG. 4 is a left side view of the dental tool reader shown in FIG. 1;

FIG. 5 is a right side view of the dental tool reader shown in FIG. 1;

FIG. 6 is a front view of the dental tool reader shown in FIG. 1; and,

FIG. 7 is a rear view of the dental tool reader shown in FIG. 1.

The broken lines shown in the drawings are included for the purpose of illustrating portions of the dental tool reader and form no part of the claimed design.

1 Claim, 7 Drawing Sheets
